UNITED STATES PATENT OFFICE.

CLARENCE YATMAN KINSEY, OF GLADSTONE, NEW JERSEY.

CLOTHES-LINE HOLDER.

1,263,680.

Specification of Letters Patent. Patented Apr. 23, 1918.

Application filed June 9, 1916. Serial No. 102,736.

To all whom it may concern:

Be it known that I, CLARENCE YATMAN KINSEY, a citizen of the United States, residing at Gladstone, in the county of Somerset and State of New Jersey, have invented new and useful Improvements in Clothes-Line Holders, of which the following is a specification.

This invention is an improved clothes line holder especially adapted for attachment to one side of a window casing and to extend into the room and providing a pulley over which the clothes line runs and which is arranged at the inner end of the holder so that the clothes line is arranged partly within the room and thus enables clothes and other articles to be placed on and taken from the line without the necessity of leaning out of the window in order to do so.

20 The invention consists in the features of construction, combination, and arrangement of devices, hereinafter fully described and claimed.

In the accompanying drawings:

25 Figure 1 is a side elevation of a clothes line holder constructed and arranged in accordance with my invention.

Fig. 2 is a plan of the same partly in section.

30 Fig. 3 is an end elevation of the same, showing the handle in a horizontal position.

Fig. 4 is an end elevation of the same, with the handle arranged in vertical position.

35 Fig. 5 is a detailed plan of the same, also showing the handle arranged in vertical position.

In the embodiment of my invention, I provide a bracket 1 which is here shown as angular in cross section and is adapted to be secured on one corner and at one side of a window casing, by means of screws or other like devices, the outer web 2 of the bracket being provided with openings 3 for said screw. The web 4 of the bracket is provided with a pair of spaced bearing lugs 5, arranged one above the other and said web is also provided at a point intermediate the pair of lugs with a circular boss 6. A bearing member 7 is arranged on the outer side of the boss 6, at the center thereof and is pivotally connected thereto by a stem 8 which engages in an opening in the center of the boss. Said bearing member extends

across the boss and is provided in its outer side with a semi-cylindrical groove 9.

An arm 10 which is preferably shaped as shown, is provided at one end with a pair of lugs 11 which bear between the lugs 5, and the said arm is pivotally connected to the bracket by pivot pins 12 which engage in registering openings with which the lugs 5 and 11 are provided. Thereby, the arm 10 is adapted to be swung inwardly from the window, to enter the room, or to be turned outwardly to a position parallel with the window. The arm 10 is provided in its outer side with a groove 13 which extends from its inner end a suitable distance and in this groove is mounted a slide 14 which may be held at any desired longitudinal adjustment by means of a bolt 15 which has a winged nut 16 and a series of adjusting openings 17 with which said slide is provided. On the outer side of the slide near the inner end thereof, is a pulley 18 which is mounted for revolution on an axle 19 and the said slide is also provided with a guard 20 for the pulley.

A pivoting and locking member 21, which is T-shaped has its stem 22 provided with a cylindrical portion 23 which passes through a correspondingly shaped opening in the arm 10. The T-shaped head 24 of said member engages in the pivoting groove 85 9 of the bearing member 7. A handle 25 which is here shown as an arm is provided at a point intermediate its ends with an offset 26 and is provided with a non-circular opening through which extends a correspondingly shaped portion 27 of the stem 90 of the member 21 and is secured on said stem by means of a nut 28.

When the arm 10 is extended inwardly from the window into the room, as shown in full lines in Fig. 2, the T-shaped end 24, of member 21, engages the groove 9 of bearing member 7 and causes the face of bearing member 7 to be pressed snugly against the face of boss 6, the member 25 is arranged 100 parallel with said arm and causes the T-shaped head 24 of the pivoting and locking member to be also parallel with said arm and arranged horizontally, so as to hold the bearing members 7 in horizontal position 105 and at right angles to the pivot axis 12 of the arm 10. The pressure between the faces of bearing member 7 and boss 6 when arm 10

is in indoor position and arm 25 is horizontal, locks the arm 10 and prevents it from turning on pivot axis 12 as can be understood from consideration of Fig. 2. To hold member 25 in horizontal position, I provide a small ball shaped projection 29 on the member 7 which fits in a correspondingly shaped indentation in the boss 6, the resilience between the parts permitting the arm 25 to be moved to the vertical thus unlocking the arm 10 and allowing it to be swung on pivot axis 12, to outdoor position as shown in Figs. 4 and 5.

When it is desired to turn the arm 10 outwardly to a position parallel with the window, as indicated in Fig. 5, the member 25 is turned to a vertical position so that it serves to engage and retain the clothes line in place and also serves to turn the head 24 of the pivoting and locking member and the bearing member 7 to a vertical position so that the pivoting head 24 is directly in line with the pivot axis 12 of the arm 10. The arm can then be readily turned outwardly as will be understood.

The endless clothes line 32 is drawn around the pulley 18 and another pulley is mounted upon a distant post, not shown. The upper run only of the line passes over the member 26 when the arm 10 is swung to position within the room, in which position clothes are hung upon the lower run, which is paid out the window as fast as it is filled. After the line is full the handle 25 is turned to a position shown in Fig. 4 and both runs of the line are turned around the upper end of the handle 25 as shown in Fig. 5. The arm may be swung out of the window to a position outside the window. To keep clothes and other articles from coming in contact with the window sill, I provide a trough 30 which is suspended from the arm 10 by means of link arms 31.

The device is reversible so that it may be

attached to either side of a window frame, 45 is small in construction, is strong and durable, and its use greatly facilitates the operation of hanging out and drying washed articles.

From the foregoing description, taken in 50 connection with the accompanying drawings the advantages of construction and of the method of operation will be readily apparent to those skilled in the art to which the invention relates, and while I have described 55 the principles of operation of the device together with the device which I now consider to be the best embodiment thereof, I desire to have it understood that the device shown is merely illustrative and that 60 such changes may be made when desired as are within the scope of the claims appended hereto.

Having described the invention, what is 65 claimed is:

1. In a clothes line support, a base member for attachment to a window casing or the like, an arm pivotally connected to the base member for movement in a horizontal plane, a pulley carried by the arm, means 70 to lock the arm in inturned position, and including a pivoting member pivotally mounted in the arm, the axis of which is adapted to be turned to a position either in line with or at right angles to the pivotal 75 axis of the arm.

2. In a clothes line support, a base member for attachment to a window casing or the like, an arm pivotally connected to the base member for movement in a horizontal 80 plane and provided with a line engaging pulley, and a trough member hung from said arm.

In testimony whereof I affix my signature,
CLARENCE YATMAN KINSEY.

Witnesses:

ELEANOR SQUIER SUTPHEN,
JOSIE SUTPHEN.
